UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

ELECTRICAL SELECTIVE SYSTEM.

Application filed March 9, 1920. Serial No. 364,553.

To all whom it may concern:

Be it known that I, CLARENCE B. FOWLER, a citizen of the United States, residing at New York, in the county of New York, State of New York, have invented certain new and useful Improvements in Electrical Selective Systems, of which the following is a full, clear, concise, and exact description.

- 10 This invention relates to electrical selective systems and more particularly to electrical selective systems for use in automatic or semi-automatic telephone exchange systems.
- 15 One of the objects of this invention is to provide in a system of this nature, a number indicating device adapted to be set under the control of an impulse sender and retained in its set position until released.
- 20 A further object of this invention is to provide an improved impulse circuit for controlling the operation of selector switches.

In accordance with one of the features 25 of this invention a plurality of step-by-step switches are adapted to be successively set in response to the sending of a plurality of series of impulses from a common impulse transmitting means. A plurality of signals, 30 preferably one for each digit of the decimal system of notation are associated with each switch. In response and corresponding to the impulses transmitted by the impulse transmitting means, signals are actuated.

- 35 Actuation of a key returns all the switches to normal, thereby deenergizing the signals.
- Another feature of the invention, while 40 employed in this invention but not necessarily limited thereto, consists in interposing a quick-acting relay between an impulse relay and a slow-acting relay usually employed in connection with a selector switch for controlling an auxiliary switch or side switch associated with the selector switch.
- 45 The purpose of this quick-acting relay is to insure actuation of the auxiliary switch at the proper time.

For a more complete understanding of 50 this invention, reference may be made to the following description considered in connection with the accompanying drawing which illustrates one embodiment of the invention.

There are shown in the drawing four 55 automatic switches, which may be of any

well-known type of step-by-step switch, as for example that shown in the U. S. Patent No. 1,472,465 of Forsberg and deVigner, issued October 30, 1923. In the particular system shown, each switch may be 60 provided with three sets of contact banks. For the purpose of this specification the lower, middle, and upper contact banks will be termed, restoring, switching and steering banks respectively. The brushes of the steering banks are slightly different from those of the restoring and switching banks in that they are of the bridging type, that is, the brushes make-before-break in passing from one contact to the next. To each steering 65 bank are connected, a plurality of signals preferably one for each digit of the decimal system of notation; through each switching bank an auxiliary switching device, such as relay 31, is controlled; and through each 70 restoring bank, an operating circuit for restoring the switches to normal is controlled.

Each switch is provided with a motor magnet, M, M such as 30, which operates under the control of the impulse sender to 80 move its associated brushes such as 32, 33 and 34. The motor magnet 30 first operates to control the signal corresponding to the digit dialed and subsequently operates to restore the switch to normal.

Each auxiliary switch, herein shown as a relay, such as 31, operates at the end of each series of impulses to connect an impulse circuit to the succeeding switch. The actuation of relay 31 is controlled by slow- 90 to-release relay 24, which is energized during the sending of impulses, and a quick-acting relay 23, which operates in response to the first interruption of the impulse circuit to operate slow-to-release relay 24. Relay 31 is thus initially prevented from operating during the sending of each series of impulses by the operation of relay 23 and subsequently by relay 24.

The nature of the invention is such that 100 it is believed a clearer understanding thereof will be obtained from a description of the operation of the system shown and it will be so described.

It will be assumed, for the purpose of 105 illustration, that an operator having access to a sender S desires to dial the number 2345. Having associated the sender with the impulse relay 20, in any well-known manner as by operating a key or inserting a plug 110

in a jack (not shown but schematically indicated by the contacts 10), relay 20, and in turn slow-to-release relay 21, are operated. The operator then proceeds to send out impulses in accordance with the desired number. Assuming that the sender S is of the well-known rotary or dial type, two interruptions of the circuit for relay 20 will occur when digit 2 is dialed. Upon the first 5 interruption of the contacts 18 of the sender S, the circuit for relay 20 is opened and relay 20 momentarily deenergizes thereby closing circuits for relay 23 and operating magnet 30, said circuits extending from 10 ground, through the armature and back contact of relay 20, armature and front contact of slow-to-release relay 21, which being slow-to-release does not retract its armature during the sending of impulses, and thence 15 in parallel, one path extending through the right-hand winding of relay 23 to grounded battery, and the other over impulse conductor 29, upper normal contacts of relay 31 and winding of motor magnet 30 to ground- 20 ed. battery. Magnet 30 in actuating moves the brushes of switch A one step into engagement with its first set of contacts. Relay 23 in energizing completes a locking circuit for itself and causes ground to be placed 25 on conductor 19, extending through the lower normal contacts of relay 31 to the strapped terminals of the switching bank 33 of switch A, thus short-circuiting relay 31 and preventing its energization at this 30 moment. This ground is supplied to conductor 19 through the outer right-hand contact of relay 26, the inner make contact of relay 23 and the left-hand normal contacts of relay 24, until relay 24 operates, whereupon 35 this ground is supplied to conductor 19 through the left-hand alternate contacts of relay 24. The locking circuit for relay 23 includes the outer right-hand contacts of relay 26, upper make contacts of relay 23, 40 left-hand winding of relay 23, and the right-hand contact of relay 24. Relay 23 in energizing also completes a circuit for the energization of slow-to-release relay 24 which, in energizing, maintains the ground on conductor 19 during the sending of each series 45 of impulses. The circuit for the energization of relay 24 may be traced as follows: grounded battery, winding of relay 24, lower make-contacts of relay 23, and outer 50 right-hand armature and back contact of relay 26 to ground. In energizing, relay 24 opens the locking circuit for relay 23, thus insuring the immediate release of relay 24, when the impulses of each set cease. Ordinarily a slow-to-release relay, such as 24, 55 which remains energized during the sending of the impulses and releases at the end of each series of impulses, is used to control the actuation of the magnet for the side switch or switching device. It has been 60

demonstrated that while relay 24 is essentially a slow-to-release relay, it is also somewhat slow-to-operate and if the impulses transmitted are not exact in character, relay 24 is apt not to function properly to control the actuation of the switching device (in this instance relay 31) associated with the selector switch; quick-acting relay 23 is, therefore, interposed between the impulse relay 20 and the slow-to-release relay 24. 70 Upon the first interruption at the sender, relay 23 operates to control the actuation of relay 31, the control being subsequently transferred to the slow-to-release relay 24. At the second interruption of the circuit 75 for relay 24, relay 20 again deenergizes in response to which motor magnet 30 is again actuated, thus moving the brushes 32, 33 and 34 a second step. 80 Following the second interruption of the contacts at the sender S, relay 20 again energizes and since the dial has now returned to normal position, relay 20 is maintained energized for an appreciable time or until the operator has set the dial for the 90 second digit. During this interval, relay 24 deenergizes thereby removing the ground from conductor 19 and permitting the operation of relay 31 over a circuit extending from ground, winding of relay 31, brush 33, 95 strapped contacts of the switching bank and resistance 35 to grounded battery. Relay 31 in operating disconnects the impulse conductor 29 from magnet 30 and connects it to magnet 40. The brushes of switch A remain upon the contacts to which they have been moved, and lamp 2 corresponding to the digit dialed is caused to glow over a circuit extending from grounded battery, contacts of key 27, left-hand normal contacts of 100 relay 26, conductor 17, lamp 2, third contact of the steering bank of switch A, and brush 34 to ground. 105

From the foregoing it is apparent that the switches B, C, and D may be successively operated in a similar manner to indicate the several digits, namely, 3, 4, and 5 dialed by the operator and thus an indication (2345) is set up in the bank of lamps corresponding to the digits dialed. 110

To extinguish the signals and return the switches to normal, restoring key 27 may be actuated whereupon all switches are simultaneously started in their movement to normal position. Actuation of non-locking key 115 27, removes the shunt from relay 26, thereby completing a circuit extending from grounded battery, through the winding of relay 26, conductor 17, lamp 2, third contact and brush 34 of switch A to ground. Parallel 120 circuits to ground extending from conductor 17 through the remaining actuated signals and their associated contacts and brushes are maintained until all switches have reached 125 their normal position. Relay 26 is ener- 130

gizing completes a circuit through the restoring bank of each switch for the motor magnet of each switch. Under the control of their respective motor magnets, the 5 brushes of each switch are returned to normal position. In reaching normal position the circuit for relay 26 is opened, whereupon relay 26 releases its armatures and the system is ready for the next operation.

10. What is claimed is:

1. In an electrical selective system, a number indicating device comprising a plurality of sets of signals, each set having one signal for each digit of the decimal system of notation, a train of switches, one for each set of signals, means for actuating certain of said signals when said switches are in their set positions, means including an impulse sender for sending a plurality of sets of impulses 15 for setting said switches, an auxiliary switching device individual to each switch of the train, and means for successively actuating said auxiliary switching devices during the intervals between sets of impulses 20 to associate the impulse sender with the succeeding switch of the train.

2. In an electrical selective system, a number indicating device comprising a plurality of sets of signals, each set having one signal for each digit of the decimal system of notation, a train of switches, one for each set of signals, means to actuate certain of said signals when said switches are in their set positions, means including an impulse sender for sending a plurality of sets of impulses to set said switches, a relay individual to each switch of the train, means whereby said relay is actuated at the cessation of the set of impulses for the switch 30 being set and means whereby said relay when energized associates the impulse sender with the succeeding switch of the train.

3. In an electrical selective system, a number indicating device comprising a plurality of sets of signals, each set having one signal for each digit of the decimal system of notation, a train of switches, one for each set of signals, means effective when said switches are in their set position to actuate certain of said signals, means including an impulse sender for sending a plurality of sets of impulses to set said switches, a relay associated with each switch of the train, means effective upon the cessation of each set of impulses to energize the relay of the switch being set, means whereby said relay upon energizing associates the impulse sender with the succeeding switch of the train, an impulse relay, and means including a quick and slow acting relay associated with said impulse relay for preventing the energization of the relay of the switch being set during the sending of a set of impulses.

4. In an electrical selective system, a number indicating device comprising a plurality

of sets of signals, each set having one signal for each digit of the decimal system of notation, a train of switches, one for each set of signals, means to actuate certain of said signals when said switches are in their set 70 positions, means including an impulse sender for sending a plurality of sets of impulses to set said switches, a relay associated with each switch of the train, means whereby the energization of said relay associates the impulse sender with the succeeding switch of the train, a shunt circuit for said relay, completed upon the initial step of the switch being operated, and means for removing said shunt when said switch has been set to 75 energize said relay to associate the impulse sender with the succeeding switch of the train.

5. In an electrical selective system, a number indicating device comprising a plurality of sets of signals, each set having one signal for each digit of the decimal system of notation, a train of switches, one for each set of signals, means including an impulse sender for sending a plurality of sets of impulses to set said switches, means to actuate certain of said signals corresponding to the set positions of the switches, a relay associated with each switch of the train, means whereby said relay upon energization associates the impulse sender with the successive switch of the train and means effective to energize the relay upon the cessation of each set of impulses comprising an impulse relay and means including a quick and slow 80 acting relay associated with said impulse relay for preventing the energization of the relay of the switch being set during the sending of a set of impulses, a release circuit for each of said switches, and means for simultaneously closing all of said release circuits.

6. In an electrical selective system, an automatic switch, a stepping magnet therefor, an auxiliary switch associated with said automatic switch, means including an impulse relay for transmitting a series of impulses to said stepping magnet, and a quick-acting relay and a slow-acting relay associated with said impulse relay for jointly controlling the actuation of said auxiliary switch.

7. In an electrical selective system, an automatic switch, means including an impulse relay for controlling said switch, a switching device associated with said automatic switch, a slow-acting relay associated with said impulse relay for controlling the actuation of said switching device, and a quick-acting relay interposed between said impulse relay and said slow-acting relay for actuating said slow-acting relay and for controlling the actuation of said switching device until said slow-acting relay is energized.

8. In an electrical selective system, an impulse sender, an impulse relay responsive

to a series of impulses from said sender, an automatic switch controlled by said impulse relay, a switching device associated with said switch, a slow-acting relay, means whereby the energization of said slow acting relay operates said switching device, a quick-acting relay energized in response to the first impulse of the series to said impulse relay for energizing said slow-acting relay and means for deenergizing said slow acting relay to operate said switching device.

9. In an electrical selective system, an automatic switch, a stepping magnet therefore, means including an impulse relay for transmitting a series of impulses to said

stepping magnet, a switching device associated with said switch, a slow-acting relay associated with said impulse relay energized during the sending of a series of impulses and deenergized at the end of a series of impulses, a quick-acting relay associated with said impulse relay responsive to the first impulse of a series of energizing said slow-acting relay, and circuit connections controlled jointly by said quick-acting relay and said slow-acting relay for controlling the actuation of said switching device. 20 25

In witness whereof, I hereunto subscribe my name this 5th day of March A. D., 1920.

CLARENCE B. FOWLER.
